(57) **CLAIM**

The ornamental design for a zippered cover of a flexible jacket for a slow cooker, as shown and described.

DESCRIPTION

FIG. 1 is a perspective view as seen from the top, front, and right side of a zippered cover of a flexible jacket for a slow cooker showing my new design;

FIG. 2 is a top plan view thereof;

FIG. 3 is a front elevational view thereof;

FIG. 4 is a rear elevational view thereof; and,

FIG. 5 is a left side elevational view thereof.

The right side elevational view thereof is a mirror image of FIG. 5.

The broken lines in FIGS. 1, 3, 4 and 5 showing the body of the jacket beneath the top cover and the zipper are used for illustrative purposes only and form no part of the claimed design.
